US0D1057818S

(12) **United States Design Patent** (10) **Patent No.:** **US D1,057,818 S**
(45) **Date of Patent:** **** Jan. 14, 2025**

(54) **ENVELOPE**

(71) Applicant: **DS SMITH PACKAGING LTD,**
London (GB)

(72) Inventors: **Wim Wouters**, Herresbach (BE); **Peter Pieraets**, Leuven (BE); **Carlos Eduardo Diaz**, Sint Jans Molenbeek (BE)

(**) Term: **15 Years**

(21) Appl. No.: **35/516,431**

(22) Filed: **Dec. 6, 2021**

(80) **Hague Agreement Data**

Int. Filing Date: **Dec. 6, 2021**

Int. Reg. No.: **DM/217893**

Int. Reg. Date: **Dec. 6, 2021**

Int. Reg. Pub. Date: **Jun. 10, 2022**

(51) **LOC (15) Cl.** **19-01**

(52) **U.S. Cl.**

USPC **D19/3**

Primary Examiner — George J Ulsh

Assistant Examiner — Andrea Marie McKay

(57) **CLAIM**

The ornamental design for an envelope as shown and described.

DESCRIPTION

1.1 : Perspective

1.2 : Front

1.3 : Back

1.4 : Right

1.5 : Left

1.6 : Top

1.7 : Bottom

The broken line showing of flaps is for the purpose of illustrating portions of the envelope and forms no part of the claimed design.

1 Claim, 7 Drawing Sheets
